United States Patent Office

Des. 206,166
Patented Nov. 8, 1966

206,166

KEY RACK

McClellan B. Conover, 1209 Kensington, Flint, Mich.

Filed Apr. 15, 1964, Ser. No. 79,511

Term of patent 3½ years

(Cl. D33—3)

FIG. 1

FIG. 2

FIGURE 1 is a front perspective view of a key rack showing my new design.

FIGURE 2 is a side elevational view taken from the left of a key rack showing my new design.

The back of the key rack is plain and unornamented.

I claim:

The ornamental design for a key rack, substantially as shown and described.
